UNITED STATES PATENT OFFICE.

HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE.

SIGNATURE-DELIVERY MECHANISM FOR PRINTING PRESSES.

Application filed March 26, 1926. Serial No. 97,634.

The object of my invention is to provide novel means for delivering a wide range of signatures with a minimum number of transfers to one or both of two delivery points located one over the other, by providing two signature delivery carriers and a common folding carrier and making the carriers of certain relative sizes and providing them with a certain number of sets of grippers, predetermined sets of grippers being used to deliver predetermined signatures, the signature delivery points being at the same time so placed and spaced as to ensure the ready removal of the signatures from the lower delivery point.

My invention more particularly comprises upper and lower packer delivery carriers, upper and lower signature deliveries and a common folding carrier, one of the delivery carriers being the same diameter as the folding carrier and the other delivery carrier being three fourths the diameter of the folding carrier, the folding carrier being provided with four equally spaced sets of grippers, the larger delivery carrier with two equally spaced sets of grippers and the smaller delivery carrier with three equally spaced sets of grippers.

A practical embodiment of my invention is represented in the accompanying drawings which illustrate in vertical longitudinal section that part of the signature delivery mechanism of a rotary web printing press which includes my invention.

The sheets cut from the web are collected and folded in any well known or approved collecting and folding mechanism, the folding carrier 1 which acts also as a transfer carrier, being shown as provided with four equally spaced sets of grippers 2, 3, 4, 5. This folding carrier is arranged to transfer various signatures, as will be hereinafter brought out, to one or both of two rotary signature delivery carriers located one over the other.

One of the signature delivery carriers, in the present instance the upper carrier 6, is shown as being three fourths the diameter of the folding carrier 1 and as being provided with three equally spaced sets of grippers 7, 8, 9. The other signature delivery carrier, in the present instance the lower carrier 10, is shown as being the same diameter as the folding carrier 1 and as being

provided with two equally spaced sets of grippers 11, 12.

The packer deliveries for the signature delivery carriers are denoted by 13 and 14 and are arranged one over the other, which packer deliveries may be of any well known or approved construction. Slitters 15 and 16 may be provided for cutting the signatures apart as they are delivered from their carriers into the packer deliveries.

It is to be understood that the positions of the smaller and larger signature delivery carriers may be reversed, although the positions shown are preferred, as it allows sufficient room for the operation of the upper packer fingers, for a convenient arrangement of the packers and for a maximum space between them for gaining ready access to the signatures in the lower packer delivery.

It will be understood that any well known or approved means, not shown herein, may be employed to drive the folding carrier and signature carriers, to operate the grippers and to operate the packer delivery fingers.

The delivery mechanism herein shown is operable to deliver signatures of 8's, 16's or 32's and particularly signatures of six 8's in duplicate, six 16's and three 32's.

When delivering six 8's in duplicate, the four grippers on the folding carrier and both sets of grippers on the lower delivery carrier 10 are used, the lower delivery carrier taking every other signature from the folding carrier and the remaining signatures being taken off by the upper three-way delivery carrier.

When delivering six 16's, two of the sets of grippers on the folding carrier and one set of grippers on the lower delivery carrier are used, thus permitting every other signature to be taken off by the upper delivery carrier.

When delivering three 32's, only one set of grippers on the folding carrier is used and both sets of grippers on the lower delivery carrier 10 are silenced, the entire product being taken off by the upper delivery carrier.

From the above description it will be seen that a minimum number of carriers are provided for delivering various signatures to one or both of the delivery points, the said delivery points being at the same time

spaced apart sufficiently to give ample room for the operation of the upper packer fingers and the removal of the product from the lower packer delivery.

5 It is evident that various changes may be resorted to in the construction, form and arrangement of the several parts without departing from the spirit and scope of my invention; hence, I do not wish to be limited 10 to the particular embodiment herein shown and described, but—

What I claim is:—

1. A signature delivery comprising two signature delivery points, two signature delivery carriers therefor, one having two 15 equally spaced sets of grippers and the other having three equally spaced sets of grippers, and a common folding carrier having four equally spaced sets of grippers 20 said grippers being operable to deliver various signatures to one or both of said delivery carriers.

2. A signature delivery comprising two signature delivery points, two signature delivery carriers therefor, one having two 25 equally spaced sets of grippers and the other having three equally spaced sets of grippers, and a common folding carrier having four equally spaced sets of grippers said grippers being operable to deliver 8's or 30 16's to both of said delivery carriers or 32's to one of said delivery carriers.

3. A signature delivery comprising two signature delivery points, two signature delivery carriers therefor, and a common folding carrier, one of the delivery carriers being the same diameter as the folding carrier and the other delivery carrier being three 40 fourths the diameter of the folding carrier, the folding carrier having four equally spaced sets of grippers, the larger delivery carrier having two equally spaced sets of grippers and the smaller delivery carrier having three equally spaced sets of grippers, 45 said grippers being operable to deliver various signatures to one or both of said delivery points.

4. A signature delivery comprising two signature delivery points, two signature delivery carriers therefor, and a common folding carrier, one of the delivery carriers being the same diameter as the folding carrier and the other delivery carrier being three 50 fourths the diameter of the folding carrier, the folding carrier having four equally spaced sets of grippers, the larger delivery carrier having two equally spaced sets of grippers and the smaller delivery carrier having three 55 equally spaced sets of grippers, said grippers being operable to deliver 8's or 16's to both of said delivery points and 32's to one of said delivery points.

5. A signature delivery comprising two signature delivery points arranged one over

the other, two signature delivery carriers 65 therefor arranged one over the other, and a common folding carrier, one of the delivery carriers being the same diameter as the folding carrier and the other carrier being three 70 fourths the diameter of the folding carrier, the folding carrier having four equally spaced sets of grippers, the larger delivery carrier having two equally spaced sets of grippers and the smaller delivery carrier having three 75 equally spaced sets of grippers, said grippers being operable to deliver various signatures to one or both of said delivery points.

6. A signature delivery comprising two signature delivery points arranged one over 80 the other, two signature delivery carriers therefor arranged one over the other, and a common folding carrier, one of the delivery carriers being the same diameter as the folding carrier and the other carrier being three 85 fourths the diameter of the folding carrier, the folding carrier having four equally spaced sets of grippers, the larger delivery carrier having two equally spaced sets of grippers, 90 said grippers being operable to deliver 8's or 16's to both of said delivery points and 32's to one of said delivery points.

7. A signature delivery comprising two signature delivery points arranged one over 95 the other, two signature delivery carriers therefor arranged one over the other, and a common folding carrier, the lower delivery carrier being the same diameter as the folding cylinder and the upper delivery carrier being three 100 fourths the diameter of the folding carrier, the folding carrier having four equally spaced sets of grippers, the lower larger delivery carrier having two equally spaced sets of grippers and the upper smaller delivery carrier having three equally spaced sets of grippers, said grippers being operable 105 to deliver various signatures to one or both of said delivery points.

8. A signature delivery comprising two signature delivery points arranged one over 110 the other, two signature delivery carriers therefor arranged one over the other, and a common folding carrier, the lower delivery carrier being the same diameter as the folding cylinder and the upper delivery carrier being three 115 fourths the diameter of the folding carrier, the folding carrier having four equally spaced sets of grippers, the lower larger delivery carrier having two equally spaced sets of grippers and the upper smaller 120 delivery carrier having three equally spaced sets of grippers, said grippers being operable to deliver 8's or 16's to both of said delivery points and 32's to one of said delivery points.

In testimony, that I claim the foregoing 125 as my invention, I have signed my name this 25th day of March, 1926.

HOWARD M. BARBER.
